CONTROL OF DIESEL AND OTHER INTERNAL COMBUSTION ENGINES

Harold Everett Hill and Leonard Burbridge, Stamford, England, assignors to Blackstone & Company Limited, Stamford, England, a British company

Application May 13, 1939, Serial No. 273,556
In Great Britain May 23, 1938

9 Claims. (Cl. 290—4)

This invention comprises improvements in or relating to the control of Diesel and other internal combustion engines.

It is an object of the invention to provide an automatic engine-starting system whereby on operation of a distant control or a relay or float switch an internal combustion engine or the like can be started without necessitating the presence of an operator. It is a further object of the invention to provide a system whereby a large internal combustion engine may readily be started.

The invention comprises in an automatic engine-starting system the combination with electrically controlled starting means for the engine and a main switch for setting the starting means in operation of a time-delay switch for cutting off the starting means a predetermined time after it has been switched on and a switch-mechanically operated by the engine when started for alternatively cutting off the starting means. The effect of the time-delay switch is to prevent the starting means from being worked unduly if the engine fails to start, while the effect of the switch which is mechanically operated by the engine is to cut off the starting means in the normal event of the engine starting, so that the starting means do not remain permanently in use.

Such a starting arrangement facilitates the operations even if an operator be present, but it is a further feature of the invention that the main switch may be electrically operated and closed automatically by a relay float switch or other means operable from a distance or in response to predetermined external conditions. In this way the set can be started without the presence of an operator.

In one form of the apparatus the time-delay switch and engine-operated switch serve to render inoperative the actuating circuit of the main switch.

It is often desirable to have an alternative to the usual electric starting motor or air starting device for setting into operation large internal-combustion engines which can be used when (as in the case of remote or automatic control) the usual systems have disadvantages. In such cases according to the present invention the starting means comprise an auxiliary engine, an electric starter for the auxiliary engine which is controlled by the main switch and means to connect the auxiliary engine when started to the main engine, the aforesaid engine-operated switch being operated by the main engine. The means to connect the auxiliary engine when started to the main engine may comprise a magnetic clutch and

a switch to operate the magnetic clutch when the auxiliary engine has been started. The switch for the magnetic clutch may be a time-delay switch the operation of which is initiated when the electric starter is energised and which operates the magnetic clutch after a predetermined interval adequate for the starting of the engine, and the engine-operated switch for cutting off the starting means may also serve to cut off the magnetic clutch.

The following is a description by way of example of one form of automatic engine-starting system in accordance with the invention:

The accompanying drawing is a connection diagram showing the various parts of the system.

The diagram indicates a main engine 11 and an auxiliary internal-combustion starting engine 12. The main engine is provided with a starting pulley 13 driven from a clutch pulley 14 on the starting engine. The clutch pulley is connected to the starting engine through a magnetic clutch indicated diagrammatically at 15. The auxiliary starting engine 12 is permanently connected by a belt 16 (or it may be direct-coupled) to an electric starting motor 17 and a starting battery 18 is provided for operating the starting motor. In order to keep the starting battery charged a trickle charger 19 is provided which is permanently in operation. The auxiliary internal-combustion engine 12 is provided with a starting handle 122 for hand starting, so that it can be started manually in case the battery should become run down for any reason.

The starting engine 12 has a fuel supply which is connected to the engine through a valve capable of being opened by energisation of a fuel solenoid 20. Similarly, the main engine is provided with a fuel solenoid 21, energisation of which will open the supply of fuel to the engine; the main engine also has a compression release device to facilitate starting which is operated by a compression release solenoid 22.

A control panel 23 is provided which comprises four electrically-operated switches 24, 25, 26 and 27 together with a knife switch 28 and a red pilot lamp 29. A starting switch 30 is provided which is connected to the control panel by circuit wires 31, 32 and may be operated at a distance from the installation either by an operator, in which case the starting or main switch will be constituted by a push button switch, or by a relay from some form of remote control or the switch 30 may alternatively be any automatically operated switch which it is desired should determine the starting of the main engine. The effect

of closing the circuit 31, 32 by means of the switch 30 is to set the starting motor 17 in movement thereby cranking the auxiliary or starting engine and setting in train the starting of the main engine 11.

The electrically-operated switch 24 is a contactor switch having contacts 34 which are closed when the winding 24 is energised. It will be seen that the contacts 34 are connected by the line 35, terminal 36 and connection 37 with the negative terminal of the battery 18. When the contacts 34 are closed the battery is connected through the contacts by the connection 38, terminal 39, line 40 to the negative terminal of the starting motor 17. The positive terminal of the starting motor is connected to the battery by the line 41. Thus, closing of the contacts 34 will set the starting motor in operation.

The main starting switch 30 is connected to the contactor winding 24 to operate it through the following circuit: from the negative terminal of the battery through contact 36, connection 37, contactor winding 24, connection 42, normally-closed relay contacts 41, connection 48, terminal 49, line 50, normally-closed contacts 51, 52 on the main engine (hereinafter described), line 53, terminal 54, connection 55, terminal 56, line 52 to the switch 30 and thence by line 31, terminal 57 and connection 58 to the positive terminal 59 which is connected by line 60 to the positive side of the battery. The knife switch 28 is in parallel with the switch 30 through connection 61 on the positive side and connection 62 from the other pole of the knife switch. Consequently, closing the knife switch at the panel itself will have exactly the same effect, namely the starting-up of the engine, as the operation of the switch 30 at a distance.

The fuel solenoid 20 of the starting engine is in parallel with the operating coil 24 of the contactor switch through lines 63, 64, terminals 65, 66 and connections 67 and 31. Therefore, when the contactor switch is operated to crank the starting engine, the fuel supply to that engine will be simultaneously begun.

In series with the fuel solenoid 20 and the contactor winding 24 there are the contacts 47 and 51, 52 already referred to. The contacts 47, although normally closed, are capable of being opened by the winding 27 which is a time-delay winding energised from the negative terminal of the battery as soon as the contactor contacts 34 are closed through the connection 68 and thence by way of the connection 48, terminal 49, contacts 51, 52, terminal 54, connection 55, switch 30 and connection 58 to the positive terminal of the battery. The contacts 51, 52 are capable of being opened by a centrifugally-operated element on the main engine. Thus, if the main engine starts normally and comes up to speed, the centrifugal device will open the contacts 51, 52 and thereby break the circuit of the contactor winding 24 and the fuel solenoid 20 and disconnect the starting motor. On the other hand, if the main engine does not start within a suitable predetermined time, the time-delay winding 27 will operate and open the contacts 47, thus quickly disconnecting the starting motor and preventing the battery from being unnecessarily run down.

The time-delay switch 27 has a pair of auxiliary contacts 70 which are closed when the contacts 47 are opened. These contacts are connected from the negative terminal of the battery through the connections 71, 72 and thence through connections 73, 74 to the pilot lamp 29. Therefore,

if the engine fails to start and the time-delay switch 27 operates, the red pilot lamp is illuminated, giving a warning of the condition of the circuit. The pilot lamp need not be mounted on the panel 23 but may be located at any control point if desired. In parallel with the pilot lamp, or as an alternative thereto, there may be a relay 130 to close the circuit of a starting device for a second engine 111, if the plant includes more than one engine; thus, if the first engine 11 fails to start, the second engine 111 is automatically set in operation. Such a switch would bear the same relation to the starting circuit of the second engine as the switch 30 bears to the starting circuit of the first engine. The second engine 111 is illustrated as being started by an auxiliary engine 112 similar to the auxiliary engine 12 of the first engine and this auxiliary engine is started by an electric starter 117 operated by a battery 118 from a starting panel 123. The starting panel 123 comprises terminals 156, 157 corresponding to the terminals 56, 57 of the starting panel 123 and connected to the contacts of the relay 130 in the same way as the contacts 56, 57 are connected to the starting switch 30 of the panel 23. The battery 118 and starter 117 are connected to terminals 136, 139, 159 corresponding to the terminals 36, 39 and 59 of panel 23 and the panel 123 is provided with internal connections and relays which duplicate the connections and relays of the panel 23. Thus the second engine 111 can be started automatically by the closing of the relay 130 exactly as the first engine 11 is started by the closing of the switch 30.

The magnetic clutch 15 is connected by lines 75, 76 to terminals 77, 78. The terminal 78 is connected by way of the terminal 49, the centrifugal switch contacts 51, 52 and the starting switch contacts 30 with the positive side of the battery, while the terminal 77 is connected by connection 79 to contacts 80 of the second time-delay relay 26 and thence by connection 37 to the negative terminal of the battery. The time-delay winding 26 is itself connected on the one hand to the negative side of the battery by the same route as the contacts 80 and on the other hand to the positive side of the battery through the connections 62, 55, the switch 30 and the connection 58. The contacts 80 are normally open but will be closed by the winding 26 a predetermined time after closing of the main starting switch 30. The auxiliary engine will therefore not be connected to the main engine to rotate it during the period in which it is being started by the starting motor 17, but after a predetermined interval the winding 26 closes the circuit of the magnetic clutch; this interval is sufficient to allow for the starting of the auxiliary engine. If the auxiliary engine starts properly, therefore, the main engine 11 will be rotated to start it after the same predetermined time interval. The fuel solenoid 21 of the main engine is energised in parallel with the winding 26 through the lines 81, 82 as soon as the starting switch 30 is actuated so that the main engine will be receiving fuel when it begins to be rotated by the starting engine.

The winding 25 constitutes a third time-delay winding, the contacts 83 of which are normally closed. These contacts convey current from the positive side of the battery through the starting switch contacts 30 by way of the connections 55, 62 and 84, delivering this current through the terminal 85 on the control panel and lines 86, 87 to the compression release coil 22 of the main en-

gine, whence it returns via terminal 88 to the negative side of the battery. Therefore, the compression release coil will be energised when the starting switch 30 is closed and the main engine 5 will start on reduced compression. After a time the winding 25, which extends from the positive connection 84 to the negative connection 72, will operate to open the contacts 83 and this time is arranged to be such as to give the main engine 10 time to be started on reduced compression, whereafter it begins to run normally.

The centrifugal switch contacts 51, 52 which cut off the starting motor 17, only operate when the engine has begun to run at a speed of, say, 15 10% in excess of the speed at which the engine is cranked by the starting engine 12 and therefore up to this time the starting motor 17 is kept going. When the centrifugal switch 51, 52 operates it will be seen from the connections which 20 have been described that it not only breaks the circuit of the contactor 24, thereby cutting off the starting motor, but also breaks the circuit of the fuel solenoid 20 of the starting engine 12 and the circuit of the magnetic clutch 15, so that the 25 auxiliary starting engine is simultaneously disconnected from the main engine and from its fuel supply and thereby brought to rest.

The main engine continues to run as long as the starting switch 30 or the knife switch 28 are 30 kept closed because its fuel solenoid 21 is directly energised by the starting switch circuit connections 58, 55 and 71. The main engine will, however, immediately be stopped when the starting connections have broken and it follows that if 35 the switch 30 is an automatic switch such as a float switch, the main engine will be brought to rest as soon as the float reaches the level necessary to open the contacts at 30, or in the case of another form of automatic switch, as soon as the 40 conditions are reached, due to the running of the main engine, which the switch is set to operate under. Consequently, the starting and stopping of the main engine with the system according to 45 the present invention may be entirely automatic, although of course the switch 28 affords an alternative hand-control.

We claim:

1. An automatic engine-starting system comprising in combination a main engine, an auxiliary starting engine, an electric starting motor for the auxiliary engine, a source of electricity for the starting motor, a main switch for connecting the starting motor to the source of electricity, an electrically actuated clutch to connect the auxiliary engine when started to the main engine to start it, a time-delay switch so controlled that its action is initiated by the means for setting the starting motor in operation, which time-delay switch is connected to the said clutch 50 to operate it so as to couple the engines at a predetermined interval after the said initiation of its action, a further time-delay switch for cutting off the starting motor from the said source a predetermined time after it has been switched on, 55 said time being longer than that of the time-delay switch for operating the electrically actuated clutch and a switch operable by the main engine when started to alternatively cut off the starting motor.
2. An automatic engine-starting system as
3. An automatic engine-starting system as claimed in claim 1, wherein the main switch is an electrically-operated switch and means are provided which are responsive to predetermined external conditions for energising the operating circuit of the main switch automatically. 5
4. An automatic engine-starting system as claimed in claim 1, wherein the main switch is an electrically-operated switch and the time-delay for cutting off the starting motor switch and the 15 engine-operated switch each act by rendering inoperative the actuating circuit of the main switch.
5. An automatic engine-starting system as claimed in claim 1, wherein the engine-operated switch for cutting off the starting means also 20 serves to cut off the electrically operated clutch.
6. An engine starting system comprising in combination an auxiliary starting engine, an electric starting motor for the auxiliary engine, a source of electricity for the starting motor, a 25 main switch for connecting the starting motor to the source of electricity, an electrically actuated clutch to connect the auxiliary engine when started to the main engine to start it, an electrically operated time-delay switch for cutting off 30 the starting motor from the said source a predetermined time after it has been switched on, the operating coil of said electrically operated switch being energized when the motor starting circuit is completed, a switch operable by the main 35 engine when started to alternatively cut off the starting motor which engine operated switch also breaks the circuit of the operating coil of the said time-delay switch, and a circuit completed by the time-delay switch, if its operating coil circuit is not broken, to energize a starting circuit 40 for a second engine.
7. An engine-starting system comprising in combination an auxiliary internal-combustion engine for rotating the main engine which is to 45 be started, an electrically actuated clutch for coupling the auxiliary engine to the main engine, an electric starting motor for the auxiliary engine, means for setting the starting motor in operation, a time-delay switch so controlled that its 50 action is initiated by the means for setting the starting motor in operation, which time-delay switch is connected to the clutch to operate it so as to couple the engines at a predetermined interval after the said initiation of its action, and 55 an automatic switch operated by the main engine after it has been started so as to terminate the operation of the clutch.
8. An engine starting system as claimed in claim 7, wherein the said automatic switch operated by the main engine serves also to terminate 60 operation of the starting motor.
9. An engine starting system as claimed in claim 7, wherein two time-delay switches are provided, one the said switch for operating the 65 clutch and the other, operating after a longer interval, for disconnecting the starting motor from operation.
